UNITED STATES PATENT OFFICE.

WILLIAM H. WOOD, OF HARTFORD, CONNECTICUT.

DEVICE FOR CONVERTING MOTION.

SPECIFICATION forming part of Letters Patent No. 349,775, dated September 28, 1886.

Application filed March 12, 1886. Serial No. 194,983. (No model.)

To all whom it may concern:

Be it known that I, WILLIAM H. WOOD, of Hartford, in the county of Hartford and State of Connecticut, have invented certain new and 5 useful Improvements in Devices for Converting Motion, of which the following is a description, reference being had to the accompanying drawings, and to the letters of reference marked thereon, where—

10 Figure 1 is a detail view, in central longitudinal section, of one of a group of cylinders, of part of the hollow shaft, and of the cams of an engine embodying my invention. Fig. 2 is an end view of the cylinder-head of a group 15 of cylinders, showing the cylindrical supports for the cross-heads and the ends of the piston-rods.

The object of my invention is to provide, in 20 an engine in which the use of a crank is avoided, such a combination of curved cams and the piston-rods as will overcome the difficulties existing in the form of curved cam-grooves in the engine described, and claimed in my application for United States Letters Patent, 25 Serial No. 171,871.

My invention consists in the combination of 30 a cylinder with a piston-rod extending through both heads thereof, and each bearing against the faces of similar cams that are both fast to a rotary shaft, and in details of the parts, as 35 more particularly hereinafter described and claimed.

So much only of the complete engine is shown as is necessary to the present invention, 35 the valve and its connected parts and the rotary shaft being broken away in the accompanying drawings.

In the accompanying drawings, the letter *a* denotes the cylinder of an engine that is 40 operated by the expansion of vapor, as steam, carbonic acid, or the like gas; *b* and *b'*, the steam-ports at opposite ends of the cylinder; *c* and *d*, the cylinder-heads; *e*, the piston; *f*, the piston-rod that extends from both sides of 45 the piston through the piston-heads, the openings through the latter being packed in the usual manner. Fast to the cylinder-heads are the ways *c' d'*, that are preferably so connected laterally as to form a continuous web that 50 resembles two open-ended cylinders projecting from the cylinder-heads, and in the walls of each are formed the grooves into which the

ends of the cross-heads project. The cross-head *c''* bears in line with the axis of the piston-rod a roller, *c'*, and the shaft of this roller 55 extends each way from the cross-head, and bears on each side a roller, *c'*, that fits in the channel between the guides or ways and serves to reduce the friction due to the lateral thrust or reaction of the cam *g'*, against the face of 60 which the roller *c'* directly bears. This cam *g'* is formed on the edge of a cylindrical cam-block, *g*, that is held on the shaft *h*, between the set-nuts *h' h''*, that fit upon a thread cut in the shaft. The cam-block is hollowed out so 65 that its outer wall projects between the open-ended cylinders in which are formed the ways for the cross-head bearing. On the opposite end of the piston-rod is fast the cross-head *d''*, bearing the rollers *d'* and *d'*, which are ar- 70 ranged precisely similar to the rollers upon the opposite end of the piston-rod, as already described, and the roller *d'* bears against the edge of the cam *i'*, formed on the edge of the cam-block *i*, which are the counterparts of the cam 75 and cam-block already described. This latter cam-block, *i*, is adjustably secured to the shaft *h* between set-nuts, so as to render it longitudinally adjustable, as in the case with the other cam-block. These cams are so secured 80 to the shaft *h* that the distance between the adjacent faces of the cams *g'* and *i'* when they are in a line parallel to the axis of the shaft is always the same, and the thrust of the piston-rods comes directly upon the cam of each 85 cam-block, and in line with the axis of the piston. The advantage gained by this construction is, that the movement of the rollers along each of the cams is continuous and in the same direction, whereas in the form and 90 arrangement of the cam-groove and the engaging-pin on the piston-rod in old devices the roller reverses its rotary motion at the end of every stroke.

Another advantage is in the adjustability 95 of the cam-blocks, by which any wear is taken up so as to prevent endwise play of the piston between the cams, and this feature is a further improvement over old devices.

In Fig. 2 the end view of a cylinder-head appurtenant to a group of six cylinders, is shown, the lateral position of the cam being shown in dotted outlines.

I claim as my invention—

1. In combination, a cylinder, a piston with its rod extending through both cylinder-heads and engaging curved cams at both its ends, and the curved cams fast to the main shaft, all substantially as described. 5
2. In combination, a cylinder, a piston with its double-ended piston-rod extending through both cylinder-heads and engaging curved cams, the ways or guides fast to and projecting from the cylinder-heads, and the hollow cam-blocks bearing the curved cams, and adjustably secured to the driving-shaft, all substantially as described. 10
3. In combination, the fixed cylinder, the rotary shaft bearing the inward-facing curved cams at all points equidistant from each other, and the double-ended piston-rod located between the cams and parallel to the shaft and bearing with its opposite ends directly against the similar cams, all substantially as described. 15 20

WILLIAM H. WOOD.
